UNITED STATES PATENT OFFICE.

WILLIAM J. LANE, OF CHICAGO, ILLINOIS, ASSIGNOR OF ONE-HALF TO MORTIMER H. SWAFFORD, OF CHICAGO, ILLINOIS.

SCRUBBING-MACHINE.

1,118,870.

Specification of Letters Patent.

Patented Nov. 24, 1914.

Application filed February 21, 1910. Serial No. 525,061.

To all whom it may concern:

Be it known that I, WILLIAM J. LANE, a citizen of the United States, and a resident of Chicago, county of Cook, and State of

5 Illinois, have invented certain new and useful Improvements in Scrubbing-Machines, of which the following is a specification.

The invention relates to scrubbing machines and seeks to provide a portable machine having an improved arrangement of power operated brushes which can be used for cleaning floors or for polishing waxed floors.

More particularly, the improvement is designed for cleaning floors and seeks to provide, in connection with the brushes, improved means for supplying water or cleansing fluid to the floor and for withdrawing the soiled water or fluid therefrom.

20 The invention consists in the features of improvement hereinafter set forth, illustrated in the preferred form in the accompanying drawings and more particularly pointed out in the appended claims.

25 In the drawings, which illustrate the preferred embodiment of the invention, Figure 1 is a front elevation; Fig. 2 is a side elevation with the side wall or plate of the casing removed; Fig. 3 is an inverted plan view; Fig. 4 is a top plan view; Fig. 5 is a partial section on the line 5—5 of Fig. 3; Figs. 6 and 7 are detail sections of the separator taken on the lines 6—6 and 7—7 respectively of Fig. 4; Fig. 8 is a detail section 30 on the line 8—8 of Fig. 5.

The body of the machine comprises an open-bottomed casing the frame of which comprises upright, corner angle-bars 10 connected at their upper horizontal ends by 35 end and side angle-bars 11 and 12 and intermediate their ends by horizontal end and side angle-bars 13 and 14. The upper set of angle-bars 11 and 12 carry a top, horizontal partition or support 15 and the set of angle-bars 13 and 14 carry a horizontal plate or support 16 intermediate the upper and lower portions of the machine frame or casing (see Fig. 5). Small supporting wheels or rollers 17 are journaled in brackets 18 that are fixed to the lower ends of the front angle-bars 10 and caster wheels 19 are journaled in supporting brackets 20 that are rotatably mounted upon the lower ends of the rear, upright angle-bars 10. A han-

dle-bar 21 is secured to the upper, rear portion of the machine so that it may be guided over the floor as desired.

A series of short, vertical shafts 22, four in number in the form shown, are journaled in suitable bearings upon the intermediate horizontal supporting plate 16. Each of these shafts is provided on its upper end above the plate 16 with a gear 24 and, below the plate, with a support or cross-arm 25 which is centrally fixed thereto. A common, central drive shaft 26 is journaled in suitable bearings in the upper and intermediate horizontal plates or plates 15 and 16 and, at its lower end, is provided with a pinion 27 which meshes with the gears 24 on the shafts 22. At its upper end, in the form shown, the drive shaft 26 is provided with a beveled gear 28 which is engaged by a beveled pinion 29 upon the shaft of a suitable motor 30 that is mounted upon the upper portion of the machine frame or casting. An electric motor is indicated in the drawings to which current could be supplied by flexible conductors without interfering with the movement of the machine over the floor but other suitable types of motors could be used for rotating the drive shaft 26 and, through it, the short, vertical shafts 22 and cross-arms or supports 25.

From the ends of the cross supports 25 depend vertical arms 31 that are preferably square in section, as shown in Fig. 8, and a series of brush holders 32 are mounted on these arms. Each brush holder comprises a square sleeve portion 33 that slidably engages the corresponding arm 31 and a pair of depending side portions or arms 34 that are spaced apart and provided at their lower edges with inturned lips 35 for engaging the back 36 of the brush 37 carried by the holder. One of the side portions or arms 34 is provided with a rib or shoulder 38 above the lip 35 and the other arm 34 is provided with a screw 39. The back of the brush fits between the shoulder 38 and the adjacent lip 35 and is centrally engaged on one side thereby and, on the opposite side, by the screw 39, so that the brush is removably clamped in position. In this way, the brushes can be readily renewed when worn out or changed in accordance with the character of the work for which the machine is used.

The brush holders are vertically slideable upon the arms 31 but are held against disengagement therefrom by cross-pins 40 in the lower ends of the arms. The parts are so arranged that, when the brushes are in contact with the floor, the sleeve portions 33 of the brush holders are held somewhat above the cross-pins 40 and the brushes and brush holders are free to rise and fall as they pass over irregularities in the floor. The brush holders are formed of comparatively heavy castings, the weight of which is sufficient to hold the brushes against the floor with the proper amount of pressure to operate effectively when the horizontal supports or cross-arms 25 are rotated by the driving mechanism.

Two tanks 41 and 42 for clean and soiled water or cleansing fluid, are mounted upon opposite sides of the upper portion of the machine frame or casing. A pipe 43 communicates with the lower end of the clean water tank 41 and two branch pipes 44 and 45 lead therefrom to a pair of horizontally disposed sprinkler pipes 46 and 47. These sprinkler pipes are provided upon their under sides with series of perforations to thereby spray the water or cleansing fluid upon the floor. The sprinkler 46 is arranged in advance of the front set of brushes and the sprinkler 47 in front of the rear set. The sprinkler 46, in the form shown, is arranged just outside the front wall of the casing, so that the portions of the floor adjacent the walls of the building can be cleaned. The walls of the machine casing are formed of thin sheet metal plates 48 which are removably secured to the angle-bar frame of the machine by screws 49. The portion of the casing above the horizontal partition 16 is preferably inclosed by one set of plates and the portion below this partition, in which the brushes are arranged, by another set. The front and side walls of the casing are provided, at their lower edges, with depending strips 50 of vulcanized rubber or like suitable, flexible material, the lower edges of which are closely adjacent the floor, so that the brushes can not throw the water or other cleaning fluid about over the floor. These strips are formed of rubber or other like material so that they will not mar the floor in case they contact therewith.

A suitable scraper is provided in rear of the brushes to collect the soiled water. This scraper comprises a strip 51 of flexible, vulcanized rubber or other like suitable material which is secured at its upper edge to a curved, metal bar 52. This bar is provided at its ends with upturned guide-rods 53 which slidably engage perforated ears 54 upon the lower ends of a pair of guide supports 55. The latter are fixed to and depend from the side angle bars 14. A rod 56

is centrally fixed to the scraper supporting bar 52 and extends upwardly through a perforated ear 57 that projects rearwardly from the end angle-bar 13. A spring 58 coiled about the rod 56 extends between the guide ear 57 and a nut 59 threaded upon the lower end of the rod and serves to hold the scraper bar firmly but yieldingly in contact with the floor. The upper end 60 of the rod 56 is outturned and may, if desired, be engaged by a hook 61 that depends from an ear 62 on the upper portion of the machine frame to thereby hold the scraper bar out of contact with the floor. This is done when, for example, the machine is used for polishing a waxed floor. The curved scraper extends from side to side of the machine in rear of the brushes and serves to collect the soiled water or cleaning fluid as the machine is pushed forward over the floor and, because of the curved form of the scraper, the soiled water is collected at the central portion thereof from which point it is withdrawn from the floor and delivered into the tank 42 by a vacuum apparatus.

The air pump of the vacuum apparatus may be of any suitable, compact type. In the preferred form of the invention, a small rotary pump 63 is mounted upon the upper, front portion of the machine frame and its shaft is provided with a beveled pinion 64 which meshes with the teeth of the beveled gear 28, so that the pump is driven, together with the brushes, from the motor 30. The inlet port of the pump communicates with a pipe 65 that leads from the upper portion of a separator 66. A suction pipe 67 opens into the upper end of the separator and the inlet end of this suction pipe is arranged, as shown, adjacent the floor and adjacent the central portion of the scraper 51.

In operation, the soiled water or cleansing fluid is withdrawn from the floor in rear of the brushes by the vacuum produced by the air pump, the water being drawn up through the suction pipe 67 into the separator 66. The water is there separated from the air and passes therefrom through a pipe 68 into the soiled water tank 42. This pipe leads from the lower portion of the separator 66 into the upper portion of the tank 42, and to prevent the back flow of either air or water from the tank, the pipe is provided with a check valve 69. To aid in separating the water from the air, the suction pipe 67 is provided with a downturned end portion or elbow 70 within the separator, as shown in Fig. 7. The tanks 41 and 42 are preferably provided with gage glasses 71 and with removable covers 72 to prevent the splashing of water therefrom. The flow of water from the tank 41 to the sprinklers 46 and 47 is controlled by a valve 73 in the pipe 43 that is operated by a rod 74 extending to the rear of the machine. The soiled water

can be withdrawn from the tank 42, through a discharge valve 75 and a reversible elbow pipe 76.

It is obvious that numerous changes may be made from the details of structure set forth without departure from the essentials of the invention.

I claim as my invention:—

1. A floor scrubbing machine comprising an inclosing casing, wheels for supporting said casing with its lower edges closely adjacent the floor, a series of vertical shafts journaled within said casing, a motor mounted on the upper portion of said casing and geared to said shafts to drive the same, cross-bars fixed to the lower ends of said shafts, pairs of vertical arms depending from the ends of said cross-bars, separate brush-holders slidably mounted on said vertical arms, but held against rotation thereon, and brushes mounted in said brush-holders, each of said holders and its brush being free to move in vertical direction independently of the other holders and brushes, and each of said brushes being held in engagement with the floor by the weight of its holder, substantially as described.

2. A floor scrubbing machine comprising a casing, wheels for supporting said casing at its lower edges closely adjacent the floor, said casing having a horizontal partition dividing the same into upper and lower compartments, a series of vertical shafts journaled in said partition, a motor mounted on the upper portion of said casing, gears in said upper compartment connecting the upper ends of said vertical shafts to the shaft of said motor, and a series of brushes mounted upon the lower ends of said vertical shafts within said lower compartment, said brushes being independently movable in vertical direction, substantially as described.

3. In a floor scrubbing machine, the combination of an inclosing casing, a series of brushes mounted to rotate in horizontal planes in the lower portion of said casing, wheels for supporting said casing with its front and side edges closely adjacent the floor to retain the water thrown out by said brushes, a curved scraper at the lower rear portion of said casing extending between the side edges thereof, spring-held in contact with the floor, a suction pipe mounted in said casing and having its lower inlet end in front of the central portion of said curved scraper, a pump on said casing for maintaining a vacuum within said pipe, and a motor independent of said supporting wheels on said casing for driving said brushes and said vacuum pump.

4. In a floor scrubbing machine, the combination with a casing, of a series of brushes

arranged to rotate in a horizontal plane in the lower portion of said casing, flexible guard strips upon the side and front edges of said casing, wheels for supporting said casing and said guard strips closely adjacent the floor to retain the water thrown outward by said brushes, a curved, scraper at the lower rear portion of said casing extending between the side guard strips, a suction pipe having its lower inlet end in front of the central portion of said curved scraper, a pump on said machine for maintaining a vacuum within said pipe, and a motor for driving said brushes and said vacuum pump.

5. A floor scrubbing machine comprising a frame, a series of brushes in the lower portion of said frame and means for drawing soiled water from the floor comprising an air and water separator mounted on said frame, an air pump connected to the upper portion of said separator for maintaining a vacuum therein, a soiled water tank on said frame communicating with the lower portion of said separator, a check valve in the communication between said separator and said tank to prevent the back flow from said tank, and a suction pipe communicating with the upper portion of said separator and having its lower inlet end arranged closely adjacent the floor, substantially as described.

6. In a floor scrubbing machine, the combination of an inclosing casing, a series of horizontally rotating brushes in the lower portion of said casing, means for spraying water on the floor in advance of said brushes, wheels for supporting said casing with its lower side and front edges closely adjacent the floor to retain the water thrown outwardly by said brushes, a curved, vertically movable, spring-held scraper mounted at the lower rear portion of said casing between the side edges thereof to collect the dirty water in rear of said brushes, and means for withdrawing the dirty water comprising an air and water separator mounted on said casing, an air pump connected to said separator for maintaining a vacuum therein, a soiled water tank communicating with the lower portion of said separator, a check valve in said communication for preventing the back flow from said tank to said separator and a suction pipe leading from the upper portion of said separator and having its lower inlet end arranged closely adjacent the floor and in front of the central portion of said scraper, substantially as described.

WILLIAM J. LANE.
